UNITED STATES PATENT OFFICE.

FREDERICK A. MESTE, OF BALTIMORE, MARYLAND.

EMERGENCY-BRAKE FOR SHIPS.

1,165,272.

Specification of Letters Patent. Patented Dec. 21, 1915.

Application filed July 1, 1914. Serial No. 848,433.

To all whom it may concern:

Be it known that I, FREDERICK A. MESTE, a citizen of the United States, residing at Baltimore, in the State of Maryland, have 5 invented new and useful Improvements in Emergency-Brakes for Ships, of which the following is a specification.

This invention relates to a combined emergency brake and rudder for marine vessels, the object of the invention being to provide means of the class referred to whereby a vessel may be quickly stopped or steered to one side or the other as may be required in case the usual rudder of the vessel should become useless or lost, the combined rudder and brake being operable from the bridge of the vessel and being easily controlled from such point.

With the above and other objects in view, 20 the invention consists in the novel construction, combination and arrangement of parts, as will be hereinafter more fully described, illustrated and claimed.

In the accompanying drawings:—Figure 25 1 is a side elevation of a portion of a vessel showing the device of this invention applied thereto. Fig. 2 is a horizontal section through one side of the same showing the hinged plate closed in full lines and open in 30 dotted lines. Fig. 3 is a detail vertical cross section through the guide ways at one side of the vessel. Fig. 4 is a diagrammatic plan view illustrating the windlasses and the runs of the cables. Fig. 5 is a detail perspective view of one of the latch rods.

Referring to the drawings A generally 40 designates the hull of a marine vessel. Arranged at opposite sides thereof are hinged plates 1 each of which is hinged along its rear vertical edge to the hull as shown at 2, leaving the opposite or forward edge free to swing rearwardly to enable the plate to serve either as an emergency rudder or 45 brake for arresting the forward progress of the vessel.

Each plate is provided at its forward edge with eyes or knuckles 3 and in the preferred embodiment of the invention these eyes or knuckles are formed on the forward extremities of substantially horizontal straps 4 which are riveted or otherwise fixedly secured to the adjacent plate 1, said straps extending entirely across the plate and being provided at their rear extremities with 50 other knuckles or eyes 5 to receive the hinge pins 2.

Journaled in the eyes or knuckles 3 of each plate 1 is a latch rod 6 provided at its top and bottom extremities with hooks or fingers 7 which are adapted to engage keepers 8 on the hull of the vessel for the purpose of locking the plate in its closed position, in which position it lies broadside against the hull of the vessel and conforms to the shape thereof so as not to interfere 60 with the movement of the vessel through the water.

Each of the latch rods is provided with two arms 9 and 10 through both of which passes a flexible cable 11 having stops 12 and 13 thereon, said cable passing through eyes in said arms so that the stops referred to may come in contact with said arms for the purpose of rocking the latch rod in one direction or the other in accordance with the 70 direction in which the cable is moved. There are two cables employed for operating the two latch rods and plates 1 and in connection with said cables, separate and independent windlasses 14 and 15 are employed, the same being mounted by preference on the bridge 16 of the vessel where the pilot stands so that he may instantly release one or both of the plates. Each cable runs through suitable fair leaders 17 and over 75 direction pulleys or sheaves 18 and is wound in opposite directions around the drum of its respective windlass so that the operator may turn the windlass in one direction to operate the latch rod and release the combined brake and rudder or by turning said 80 windlass in the opposite direction he may restore said combined rudder and brake to its closed position and at the same time lock it by means of the latch rod. There is sufficient frictional engagement between the 85 latch rod 6 and the eyes 3 to prevent the turning of said latch rod until the plate 1 has come in contact with the hold of the vessel when by pulling on the cable and 90 overcoming said frictional resistance, the fingers 7 are caused to engage the keepers 8. It will be understood that the closing of the 95 plate 1 is effected while the vessel is at a standstill and the closing of the plate without the operation of the latch rod may be 100 insured by reversing the propeller and backing the vessel so that the current of water from the propeller as well as that produced by the backing action of the vessel will act 105 against the plates on both sides to return the same to their closed positions. A single

110

cable thus controls each of the plates 1 together with the latch rod thereof, the said plate being below the water line of the vessel so as to obtain the full action of the 5 water thereon.

In order to limit the rearward movement of the plates 1, each plate is controlled by a plurality of stays 19 preferably in the form of rods the rear extremities of which are 10 journaled on the adjacent latch rod as shown. Two or more of these stay rods may be employed in accordance with the size of the vessel and the plate 1 in order to equalize the strain on the plate and prevent the same 15 from being twisted or bent by the action of the water. Each of said stay rods is provided at its forward extremity with a runner 20 which is movable in a fore and aft direction in a slotted guide 21 shown as 20 formed by two parallel flanged plates 22 and 23 fixedly secured to the side of the vessel. The length of the stay rods is preferably such as to stop the rearward movement of the 25 adjacent plate 1 when the latter stands in a position about perpendicular to the longitudinal axis of the vessel.

The windlasses may be operated either by motive power or hand power as may be preferred. As soon as the windlasses are turned 30 in the proper direction, the plates are unlatched and are thereupon caught by the water and swung to their working position where they act to quickly check the forward progress of the vessel. In case the rudder 35 becomes lost or the steering gear gets out of order, the pilot may release the plate 1 either on the starboard or port side of the vessel for the purpose of steering the vessel to starboard or port as may be necessary at 40 the time. The mechanism referred to thus acts both as an emergency rudder and as a brake and is under the immediate control of the pilot or his assistant on the bridge of the vessel.

In addition to the controlling means hereinabove described, it may be found desirable in some cases to provide the runners 20 with rack bars 24 as shown in Figs. 1 and 2, said 45 rack bars meshing with pinions 25 on shafts 26 located at opposite sides of the hull and journaled in bearings 27 thereon. The shafts 26 may be controlled by any suitable means to provide for the rotation thereof and in this way the emergency rudders may be 50 opened and closed to any desired extent without permitting them to spring suddenly open to their full extent.

What I claim is:—

1. The combination with a vessel's hull, of

plates lying in close broadside contact with 60 said hull and hinged along their rear edges thereto, latch rods journaled in bearings on the forward edges of said plates, keepers on the hull adapted to be engaged by said latch rods, flexible operating cables connected to 65 said latch rods and each movable in opposite directions to move said latch rods to latching and unlatching positions and to swing said plates on their hinges, and operating means for said cables.

2. The combination with a vessel's hull, of 70 plates lying in close broadside contact with said hull and hinged along their rear edges thereto, latch rods journaled in bearings on the forward edges of said plates, keepers on the hull adapted to be engaged by said latch rods, flexible operating cables connected to 75 said latch rods and each movable in opposite directions to move said latch rods to latching and unlatching positions and to swing said plates on their hinges, and means for operating said cables independently of each other.

3. The combination with a vessel's hull, of 80 plates lying in close broadside contact with 85 said hull and hinged along their rear edges thereto, latch rods journaled in bearings on the forward edges of said plates, keepers on the hull adapted to be engaged by said latch rods, a plurality of arms at an angle to each 90 other on each latch rod, flexible operating cables connected with the arms of each of said latch rods and each movable in opposite directions to move said latch rods to latching and unlatching positions and to 95 swing said plates on their hinges, and operating means for said cables.

4. The combination with a vessel's hull, of 100 plates lying in close broadside contact with said hull and hinged along their rear edges thereto, latch rods journaled in bearings on the forward edges of said plates, keepers on the hull adapted to be engaged by said latch rods, stays connected at their rear extremities to said latch rods and having a sliding 105 connection at their forward extremities with the hull, flexible operating cables connected to said latch rods and each movable in opposite directions to move said latch rods to latching and unlatching positions and to 110 swing said plates on their hinges, and operating means for said cables.

In testimony whereof I affix my signature in presence of two witnesses.

FREDERICK A. MESTE.
